RURAL MAILBOX

George W. Stallings, Chagrin Falls, Ohio

Application October 5, 1953, Serial No. 27,077

Term of patent 14 years

(Cl. D74—9)

To all whom it may concern:

Be it known that I, George W. Stallings, a citizen of the United States, residing at Chagrin Falls, Cuyahoga County, Ohio, have invented a new, original, and ornamental Design for a Rural Mailbox, of which the following is a specification, reference being had to the accompanying drawing, forming a part hereof.

Fig. 1 is a front and side perspective view of a rural mailbox showing my new design.

Fig. 2 is a side elevational view thereof.

The rear of the box is conventionally plain and the undisclosed side presents an appearance similar to that of the side shown in the drawing.

I claim:

The ornamental design for a rural mailbox, as shown and described.
